UNITED STATES PATENT OFFICE.

SAMUEL LUCAS, OF POQUETANUCK, CONNECTICUT.

ARTIFICIAL HAND.

SPECIFICATION forming part of Letters Patent No. 429,243, dated June 3, 1890.

Application filed March 17, 1890. Serial No. 344,083. (No model.)

To all whom it may concern:

Be it known that I, SAMUEL LUCAS, a citizen of the United States, residing at Poquetanuck, in the county of New London and State of Connecticut, have invented certain new and useful Improvements in Artificial Hands, which improvements are fully set forth and described in the following specification, reference being had to the accompanying two sheets of drawings, in which—

Figure 1 is a side view of a hand embodying my improvements, and Fig. 2 a view of the same from the back or top side. Fig. 3 is a sectional view on line $z z$ of Fig. 2; and Fig. 4, a similar view of those portions adjacent to the hinge-joint, but with the spring-pawl thrown out of engagement with the ratchet-teeth, as hereinafter described. Fig. 5 is a sectional view on line $x x$ of Fig. 1, and Fig. 6 is a perspective view of the thumb detached from the hand and inverted to expose the tenon or boss by means of which it is strongly connected with said hand. In Fig. 7 I have shown the index-finger with a fork attached thereto, and in Fig. 8 an end view of the clamping-ferrule v , by means of which said fork or any similar tool may be attached to said finger.

The object of my invention is to provide an artificial hand that may be used to perform certain kinds of manual labor, which shall be strong and serviceable and cheaply constructed.

Referring to the drawings, the letter a denotes the body or main section of the hand, made of wood or other light material. This section a is provided with a shank b , that is fitted to enter a socket in a false wrist secured to the stump of the arm in any of the ways common to this class of devices.

So far as I am familiar with the methods of securing artificial hands to the stump it has been a common practice to provide a shank substantially like my shank b in outward appearance, but fastened rigidly in the hand-section. In the hand here shown the said shank is pivotally secured in a recess in said hand by a screw or pin c , as shown in Figs. 3 and 5, and is held normally in alignment with the hand by a bow-spring d , made of flat spring metal, whose free ends support

the shank b on either side. This construction relieves the rigidity which otherwise would result and prevents any sudden and painful shock to the natural stump of the 55 wearer. When lateral pressure is brought to bear on the artificial hand, the spring d may yield, as shown in dotted lines in Fig. 5; but said spring is of sufficient strength to return the hand to its normal position when such 60 pressure is removed.

Section a is slotted to receive a set of artificial fingers e , that are hinged in place by a rod or pintle f , extending through the entire series, and each of said fingers is formed at 65 its inner or hinge end with ratchet-teeth g , that are preferably concentric with the pintle f . A spring-pawl h is provided to operate with each finger, said pawl being screwed to the back side of section a , and preferably 70 formed of a single piece of slotted sheet metal, as shown. When one or all of the fingers are swung on their hinges, as in the act of closing the fingers, the described spring-pawls drop in the rear of the ratchet-teeth and hold said 75 fingers firmly in the positions to which they have been adjusted until the pawls are raised, which is accomplished through and by means of a flattened bar i , that lies in a channel in section a under the pawls h and near the free 80 ends of said pawls. One end of this bar i is bent at a right angle to form an operating-handle k . When it is desired to raise the pawls h from the ratchet-teeth, it is only necessary to depress the operating-handle k and 85 thus rock bar i into the position shown in Fig. 4, when the pawls are all raised and the fingers may be returned to their extended position. A guard-plate m may be provided to protect the operating-handle k , and also to 90 limit its downward movement, although such a plate is not absolutely necessary.

In connection with each finger I provide a spring n for automatically returning the fingers to their extended position when the pawls 95 are raised. These springs, as here illustrated, consist of rubber bands or strips having one end fastened by screw o to the back of the hand and the other end or loop attached to a wire eye q , secured to the finger. When 100 the pawls h are disengaged from the ratchet-teeth, these springs n immediately contract

and draw the fingers back to their extended position. Springs of wire could be substituted for the described rubber bands, if desired; but I find the latter cheap and effective and easily replaced when worn out or broken.

The thumb *r* of my artificial hand is hinged to the side of section *a* by a screw *s*, and while allowed to move freely on the pivot thus provided is limited in such movement by a projecting portion *s'*, that may abut a corresponding projection *t* on section *a*, as best shown in Fig. 1. To insure great strength to thumb *r*, I have provided on it a boss or tenon *r'*, that is concentric with the pivot-screw *s* and enters a corresponding mortise in section *a*.

The first and second joints of the several fingers of my artificial hand are intentionally partially closed at all times and are so constructed for the following reason: When said fingers are swung around toward the palm of the hand, they then form a hook (see Fig. 3) of great strength, by means of which various things may be lifted—as, for example, the bail of a pail or of a coal-hod—whereas if said first and second joints were in line with the ratchet-joints so perfect a hook could not be formed.

Various tools may be attached to the fingers, one of which—a fork—is illustrated in Fig. 7. Said fork is provided with two ferrules through which the finger passes, one of which *v* is formed of two overlapping plates of spring metal, (shown most clearly in Fig. 8,) that clasp the finger firmly and prevent the accidental displacement of the fork.

My artificial hand as a whole is strong and serviceable, is not expensive to make, and

enables one crippled by loss of a hand to perform many duties otherwise impossible.

Having described my invention, I claim—

1. In combination with a palm having

hinged thereto a series of fingers with ratchet-

teeth, a corresponding series of spring-pawls,

as set forth, and a corresponding series of 45

springs connecting the said palm and fingers,

substantially as and for the purpose specified.

2. In an artificial hand formed, essentially,

of a series of hinged fingers with ratchet-teeth

and pawls, as set forth, and in combination

therewith, a thumb pivotally attached to said

hand and formed with a strengthening-boss

that is seated in a mortise in said hand, sub-

stantially as specified.

3. In an artificial hand, a series of hinged 55

fingers with ratchet-teeth, a corresponding

series of pawls engaging said teeth, and

means, as set forth, for raising said pawls, the

said fingers being rigid from the hinge-joint

outward and partly closed, as and for the 60

purpose specified.

4. In combination with an artificial hand,

a shank pivoted therein and arranged to yield

laterally under pressure and a spring, sub-

stantially as described, for holding said shank 65

normally in alignment with the hand.

5. In an artificial hand, a series of hinged

fingers with ratchet-teeth, a corresponding

series of pawls engaging said teeth, and a

fork or similar tool clamped to one of said

fingers by a spring-ferrule, as described.

SAMUEL LUCAS.
